METAL CASTING SYSTEM

Friedrich Nielsen, Muhlacker, Germany

Application September 20, 1954, Serial No. 457,148

6 Claims. (Cl. 22—134)

This invention is directed to a process and apparatus for the casting of metals.

This invention is an improvement on the casting process and apparatus disclosed in my co-pending application entitled "Casting Metals," filed January 9, 1953, Serial No. 330,479, now Patent No. 2,735,147, issued February 21, 1956. In said application I disclosed a runner system in which the energy of the flowing metal in a covered channel could be dissipated by causing the metal to flow around a number of abrupt turns.

The objects of the instant invention are to produce a method and a runner system in which the metal is led through uncovered, or open, channels in such a way that the energy is dissipated and the metal led into a mold in a non-turbulent, non-foaming condition.

In general, the objects are accomplished by causing the molten metal to flow through a series of open channels of successively increasing size, and having means for causing the metal to lose energy in the channels. The end or outlet channel can extend perpendicularly or substantially so, and is connected to the conventional gates on a mold which extends over substantially the entire height thereof. The first or inlet channel section can receive metal from a preliminary runner extending in the general direction of the channel sections. Such runners can be filled from below through a deflected inlet or through any other known means. They can also be connected to various points of the channel system in the manner disclosed in my aforesaid application, Serial No. 330,479. The runners can be filled from above or connected in the form of downwardly extending branches as again shown in said application, Serial No. 330,479. Finally, the preliminary runners can be formed as inlet runners constructed according to the general formula:

$$f = 0.0226 \times \frac{m \times V}{h^n}$$

in which "f" is the runner cross-sectional area, "h" is the distance of fall of the metal, "V" is a value which equals, or is proportional to, the volume of molten metal flowing through the system per second, "m" is a coefficient between 1 and 5, "n" is for an exponent between 0.5 and 1.5. Again these special inlet channels can be filled either directly from above, as from a hopper or an adjacent gate system.

The open channels can merge into a reinforced riser which extends in the general direction of the open channel sections, and the riser is then connected to the individual gates or a single gate, leading into the mold, and then functions as a riser in the solidifying of the metal.

The means by which the objects of the invention are obtained is described more fully with respect to the accompanying drawings, in which:

Figure 1 is a perspective view of a plurality of open channel sections according to the invention, and

Figures 2 and 3 are perspective views of modifications of the invention.

In Figure 1 a plurality of channel sections 2, 4, 6, 8

2

and 10, are connected at angles to each other. The metal flowing through these channel sections from the inlet or preliminary runner 12 loses energy, and the flow velocity is reduced by the angles between the sections, 5 and by the fact that each succeeding channel is wider than the previous channels. The angles between the sections range from 20° to 150°, preferably from 60° to 90°. In Figure 1, 60° angles have been shown. The successive channel sections are widened at a ratio of about 10 1.20 to 1.28. The metal flows substantially horizontally through the sections. Depending upon the ratio applied to the widening of the channel sections, the top surface of the flowing metal inclines more or less downwardly from section 2 to section 10, and also within each of the 15 channel sections.

The metal flows from a head in runner 12, corresponding to the level of the metal to be cast in the mold. It flows successively through sections 2 to 10 with a constantly decreasing velocity, and without turbulence, splashing, or foaming. In Figure 1 channel section 10 can function as a direct gate to the mold, which in this case has thick walls.

Figure 2 is a perspective view of a modified channel system. From the preliminary runner 14 extend channel sections 16, 18, 20, 22 and 24, in succession. The channel sections are not connected at angles to each other as in Figure 1, but angled walls are included in the system, and serve to dissipate the energy of the flowing metals, but maintaining the horizontal flow of metal. In channel 25 section 18 the walls are bent into angles which serve as corners to interfere with the flow of metal and thus reduce the velocity of flow. The cross-sectional area of channel section 18 is increased over that of section 16, while the cross-sectional area of the next section 20 is 30 decreased from that of channel section 18, although it is increased over that of channel section 16. Thus, from channel section 16 through section 20 the cross-sectional area is first increased in section 18 and then restricted in section 20 of a short distance. Similarly, the next section 20 22 is increased, and then decreased in section 24. The width of sections 16, 20 and 24, is continuously enlarged, thus taking into account the desired slowing down of the velocity of flow. The loss of energy occurs by reason of the narrow walls, or at the corners between the alternately 45 spaced angled wall sections. There is also a loss of energy due to local turbulence, which occurs without foaming, and also a further loss of energy as the metal flows in two branches from the corners of sections 18 and 20, which branches merge before entering the next narrow 50 section. The amount of loss of energy is determined by the ratio of enlargement of each of the restricted channel sections. No exact mathematical and physical formula can be given for it because there are a plurality of interconnecting causes. However, the total loss of energy can 55 be empirically decided.

The system of Figure 2 can be modified by increasing the area of the channel sections in an upwardly directed conical manner. Such enlargements must not apply likewise to both the channel sections 16, 20 and 24, and the 60 intermediate sections 18 and 22. The general purpose of the upwardly directed enlargements, either in the form of cones or steps, is to reduce the total resistance of flow in the upper portion of the channel sections in order to force the hotter metal flowing in from runner 12 to the top of the casting in the mold. This effect can also be achieved or increased by omitting either gradually or abruptly one of the channel sections. If simple castings are to be made in which no special quality is sought, it is sufficient to use a system having but two small short 65 channel sections and one intermediate section, such as the use of sections 16, 18 and 20, alone.

In Figure 3 the channel section is somewhat similar to

Figure 2, but is asymmetrical. The preliminary runner 26 is filled from above. The metal flows through channel sections 28, 30, 32, 34 and 36, into a riser 38. This riser is connected with the individual gates 40, leading into the mold. The effects of reducing the velocity of the molten metal are achieved in Figure 2 by means of the angled walls of sections 30 and 34, which are connected with intermediate constricted sections.

A gate system as herein described, and also in combination with the system disclosed in my application Serial No. 330,479, has advantages both in molding and casting techniques. For example, in complicated castings one mold or model plane can be omitted. Such particularly happens when the bottom part of a casting can be made by simple ordinary pouring. Here the lowest parts of the mold cavity are reached through the open by the new channel system without frothing, in spite of the falling flow of metal. Also in the permanent mold casting of pieces having particularly thin walls, the dividing or separating plane of which stands perpendicular, the disclosed channel system is very successfully used. On the other hand, in the casting of pieces having extremely thick walls, the disclosed channel system can cast the metals at lower speeds than have heretofore been used.

Having now described the means by which the objects of the invention are obtained, I claim:

1. A casting system for leading metal into the gates of a mold comprising a plurality of open channel sections of substantially even height connected together to a channel system, each channel section from the inlet end to the outlet end of said system being increased in cross-sectional area with respect to a prior section for reducing the velocity of the metal flowing through the channel

system, and angle means for the channel sections for further reducing the metal-flow velocity.

2. A system as in claim 1, further comprising channel sections of rectangular cross-section and having a height greater than their length, and said channel sections being connected to each other at angles ranging from 20° to 150°.

3. A system as in claim 1, further comprising channel sections alternately enlarged and constricted sections with like-shaped sections being progressively enlarged toward the outlet end of the channel system.

4. A system as in claim 3, further comprising angled walls for the enlarged channel sections.

5. A system as in claim 1, further comprising a vertical preliminary runner connected to the inlet end of said channel system, said runner being open at the top and having a downwardly decreasing cross-sectional area.

6. A system as in claim 1, further comprising a preliminary inlet runner for said channel sections constructed according to the formula:

$$f = 0.0226 \times \frac{m \times V}{h^n}$$

wherein "f" is the runner cross-sectional area, "h" is the distance of fall of the metal, "V" is a value equal or proportional to the volume of metal flowing through the system per second, "m" is a coefficient between 1 and 5, and "n" is for an exponent between 0.5 and 1.5.
